UNITED STATES PATENT OFFICE.

HAROLD J. BELL, OF GLOUCESTER CITY, ASSIGNOR TO THE WELSBACH INCANDESCENT GAS LIGHT COMPANY, OF JERSEY CITY, NEW JERSEY.

GAS-INCANDESCENT.

SPECIFICATION forming part of Letters Patent No. 396,322, dated January 15, 1889.

Application filed July 2, 1888. Serial No. 278,738. (No model.)

To all whom it may concern:

Be it known that I, HAROLD J. BELL, a citizen of the United States, residing at Gloucester City, in the county of Camden and State of New Jersey, have invented new and useful Improvements in Gas-Incandescents, of which the following is a specification.

This invention relates to gas-incandescents of the character known as "mantles" or "tubular hoods," which are made by saturating a loosely-woven fabric of cotton threads with a solution of the salts of the rarer metals that produce earthy oxides, and subsequently burning out the textile fabric in such a manner as to leave a skeleton-like frame or mantle consisting of a net-work of the earthy oxides resulting from the decomposition of the salts contained in the solution with which the fabric was treated.

Heretofore the textile fabric in tubular form has been cut into suitable lengths for mantles, each of which is re-enforced at its upper end by turning a portion of the tubular fabric inward, either before or after saturation of the fabric, a fine platinum wire being subsequently threaded through the upper turned-in portion of the tubular textile frame to draw that end together, leaving a contracted rounded aperture at the top, said wire or wires being extended beyond the textile tube, on opposite sides, for attachment to a horizontal ring on the end of a rod, by which the completed mantle is to be supported above a burner. This manner of suspending the mantle during the process of manufacture and for subsequent use as an incandescent device does very well in the case of mantles of moderate diameter, which are subjected to but little strain while held in a suspended position.

When, however, the mantle is made of large diameter, for the purpose of affording an extensive incandescing-surface, it becomes necessary to provide adequate means for suspending it in such a manner that the increased strain due to its large diameter will not cause it to sag or collapse at any point, the object being to maintain the mantle in a symmetrical rounded form, curving around and above the flame, so as to attain the best illuminating effects with economy in consumption of gas

and in the duration or life of the mantle, which can be made to endure much longer by preserving its proper form. This is accomplished by re-enforcing or doubling the upper end of the large mantle to a greater depth than is required in mantles of small diameter employing a platinum wire at or near the upper turned-in edge of the tubular fabric simply for the purpose of gathering that end into proper form with the usual rounded aperture, and, finally, by threading a platinum wire in a circular direction around and through the lower edge of the turned-in portion or re-enforcement and through the body of the fabric opposite said edge, and attaching doubled and diverging platinum suspending-wires, preferably four in number, at eight equidistant points on the circularly-arranged platinum wire, thus enabling the mantle to be supported without strain from points at such distance below its top as will correspond very nearly with its full diameter, which is thus maintained in a substantially rounded form throughout.

The invention is illustrated in the annexed drawings, in which—

Figure 1 represents the tubular mantle fabric of textile net-work with its upper end turned inward or doubled to form a re-enforcement. Fig. 2 shows the tubular net-work gathered at the top by a platinum wire, with another platinum wire threaded through the fabric at the lower edge of the re-enforced portion. Fig. 3 is an elevation of the mantle fabric suspended from its support and ready for burning out the textile material. Fig. 4 is a plan of the same, showing the arrangement of the platinum suspending-wires.

By referring to the drawings, it will be observed that the numeral 1 designates the tubular mantle fabric; 2, its upper turned-in, doubled, or re-enforced portion; 3, the platinum wire by which the upper end of the tubular fabric is gathered; 4, the contracted aperture thus formed in the upper end of the mantle; 5, the circular platinum wire passed through the lower edge of the re-enforcement and through the corresponding body portion of the mantle; 6, the doubled and diverging platinum suspending-wires; 7, the ring to which said suspending-wires are attached;

and 8 the supporting-rod to which said ring is attached or on which it is formed.

The platinum suspending-wires 6 are doubled, and the ends of the several wires are attached at different points to the circularly-arranged platinum wire 5, there being eight points of attachment, at uniform distances apart, when four suspending-wires are used, as shown in Fig. 4.

- 10 I do not wish to confine myself to any particular number of suspending-wires—as three, five, or a greater number may be used instead of four; but I prefer to employ four of these wires, with their eight equidistant points of attachment, as shown, thereby preserving a more perfectly circular form of mantle; and even if the circular arrangement of the platinum wire 5 should be affected by the attachment of the suspending-wires at eight points, any tendency 15 to draw the wire 5 into an octagonal path would not appreciably alter the circular form of the mantle.
- 20 The doubled and diverging suspending-wires 6 are attached to the ring 7 by simply twisting or coiling said wires around the ring at suitable intervals to support the mantle in a central position, sufficient slack being afforded to permit the lower edge of the re-enforced portion of the mantle to sink slightly 25 below the supporting-ring, as shown in Fig. 3. By this means the strain on the wire 5 and attached mantle is reduced to a minimum, and

the mantle will maintain its proper rounded form without any liability to collapse under the effects of ordinary usage.

35

Having been prepared and attached to its support in the manner above described, the mantle fabric, which has been previously treated with a solution of metallic salts in the well-known manner, is fired to consume the textile material, and the resulting mantle of refractory oxides is left attached to its support for subsequent use as an incandescent device.

Having thus described my invention, I 45 claim—

The combination, with a mantle or tubular incandescent device having a turned-in or reinforced upper portion, of a platinum gathering-wire, 3, threaded through the upper part 50 of the re-enforcement, a platinum wire, 5, threaded through the lower part of said reinforcement in a circular direction, a number of doubled and diverging platinum suspending-wires, 6, attached at equidistant points to 55 and, around the circularly-arranged wire 5, and a circular support for said suspending-wires, substantially as described.

In testimony whereof I affix my signature in presence of two witnesses.

H. J. BELL.
